UNITED STATES PATENT OFFICE.

IRA L. FRENCH, OF CHICAGO, ILLINOIS, ASSIGNOR TO THE MANTLE LAMP COMPANY OF AMERICA, OF CHICAGO, ILLINOIS, A CORPORATION OF ILLINOIS.

DESIGN FOR A SHADE.

50,098.

Specification for Design.

Patented Dec. 26, 1916.

Application filed September 27, 1916. Serial No. 122,566. Term of patent 14 years.

To all whom it may concern:

Be it known that I, IRA L. FRENCH, a citizen of the United States, resident of Chicago, in the county of Cook and State of Illinois, have invented a new, original, and ornamental Design for Shades, of which the following is a specification, reference being had to the accompanying drawing, forming a part thereof.

In the drawing: Figure 1 is a plan view of a shade showing my new design, and Fig. 2 is a side elevation of the shade.

I claim:

The ornamental design for a shade as shown.

IRA L. FRENCH.
